L. KOBASH

ICE CAN SUBMERGING DEVICE

Filed May 3, 1924

Patented Oct. 23, 1928.

1,688,815

UNITED STATES PATENT OFFICE.

LOUIS KOBASH, OF MAPLE SHADE, NEW JERSEY.

ICE-CAN-SUBMERGING DEVICE.

Application filed May 3, 1924. Serial No. 710,885.

My invention relates to a novel construction of a device for submerging ice cans to any desired or requisite depth, and comprises a bar adapted to be supported on the top of 5 an ice can and provided with keepers at its ends in which are slidably mounted the bolt ends of a tension device composed of a central eye, and diverging arms having their terminals deflected in opposite directions to form 10 bolts which latter are adapted to engage suitable locking means supported in a brine tank in any suitable manner.

It further consists of the novel combination of a tension device of the character above 15 described, which is adapted to coact with a bar having keepers or guiding means on the ends thereof.

It further consists of other novel features 20 of construction and advantage, all as will be hereinafter fully described and pointed out in the claim.

For the purpose of illustrating my invention, I have shown in the accompanying drawings forms thereof which are at present 25 preferred by me, since they will give in practice satisfactory and reliable results, although it is to be understood that the various instrumentalities of which my invention consists can be variously arranged and organized and 30 that my invention is not limited to the precise arrangement and organization of these instrumentalities as herein shown and described.

Figure 1 represents a plan view of an ice 35 can submerging device embodying my invention.

Figure 2 represents on an enlarged scale a 40 vertical section on line 2—2 Figure 1.

Figure 3 represents a section on line 3—3 Figure 1.

Figure 4 represents a plan view of one of the slotted plates employed.

Figure 5 represents a vertical sectional view of a modification.

Figure 6 represents on an enlarged scale, the bolt forming part of my novel device.

Similar numerals of reference indicate corresponding parts in the figures.

Referring to the drawings,

1 designates a brine receptacle having 50 therein a frame composed of the upper vertical partitions 2 on which the cover 3 is supported and the intermediate partitions 4 whose upper edge may be below said cover.

55 5 designates an ice can positioned in the

brine 6 so that its top is located between a pair of partitions 2 and 4, to the inner opposed surfaces of which are secured the plates 7 having slots 8 therein, the slots in a pair of plates being disposed in horizontal alignment.

9 designates a bar resting on the top of an ice can but disconnected therefrom and provided at its ends with the horizontally extending guides or keepers 10 through which 60 pass the bolt like ends or terminals 11 of the tension devices 12. These tension devices are preferably made from a single piece of resilient wire bent to form a central eye 13 from which diverge the arms 14, which are bent to 65 form the aligning bolt-like members 11 which extend in opposite directions and are guided in the keepers 10, as stated, so that by compressing the arms 14 the bolt ends will be brought together or disengaged from the 70 slots 8 of the plates 7.

The tops of the keepers 10 are slotted as at 75 15, so as to form guides for the vertical pins or abutments 16 which project upwardly from the bolts 11, the terminals of said slots forming stops to limit the extent of movement of said pins, as is evident from Figure 80 3. If desired, the pins may be placed outside the keepers 10, as indicated at 21, Figure 6. The pins or abutments 16 may be secured 85 with respect to the bolts 11 in any desired manner. For instance, the pins or abutments 16 may be welded to the bolts 11, although obviously other forms of attachment may be practiced.

The eye members 13 of the tension devices 90 12 are preferably disposed on a pair of cams in opposite directions, as will be understood from Figure 1.

The central portion of the bar 9 is depressed or provided with a semi-spherical seat or socket 17 in which the ball member 18 is movably mounted, said ball member carrying the pendant open ended tube 19, having the ports 20 therein, it being apparent 100 that said tube is free to oscillate in any and every direction within a tank 5.

If desired in lieu of the slotted plates 7, oppositely located racks 22 having rack teeth 23 may be employed in conjunction with the 105 bolt ends 11, as seen in Figure 5.

The operation is as follows:

The ice can 5 filled with the liquid to be frozen is submerged in the brine, and the bar 9 placed thereon. The arms 14 of the tension 110

device 12 are manually compressed and when the can has been submerged to the desired extent, they are released and the bolt ends 11 engage the slots 8 or the ratchet teeth 23, 5 whichever may be employed, and hold the ice can submerged to the desired extent. The pendant air tube 19 which is free to swing in any direction into which air is introduced by any suitable means, facilitates the proper 10 freezing of the liquid, as is evident. The tension device 12 can be cheaply manufactured, and is simple and effective in its operation.

It will now be apparent that I have devised a novel and useful ice can submerging device 15 which embodies the features of advantage enumerated as desirable in the statement of the invention and the above description, and while I have, in the present instance, shown and described a preferred embodiment there- 20 of which will give in practice satisfactory and reliable results, it is to be understood that such embodiment is susceptible of modi-

fication in various particulars without departing from the spirit or scope of the invention or sacrificing any of its advantages. 25

Having thus described my invention what I claim as new and desire to secure by Letters Patent, is:—

In a device of the character stated, a bar 30 adapted to rest on the top of an ice can, thin, flat keepers on the ends of said bar having rectangular slots in the tops thereof, a tension device consisting of a wire member coiled and bent to form a single central eye, 35 which eye is horizontally disposed and is arranged in substantially the same horizontal plane as the said keepers, and arms diverging V-shaped therefrom, in substantially the same plane with said eye and having their ends deflected in opposite directions to form bolts slideable in the slots of said keepers, and upright pins on said bolts projecting through said slots in said keepers. 40

LOUIS KOBASH.
